CLAIM

The ornamental design for a cable guide for variable speed transmission such as derailleurs, as shown.

DESCRIPTION

FIG. 1 is a top plan view of a cable guide for variable speed transmission such as derailleurs;

FIG. 2 is a side elevational view thereof;

FIG. 3 is a right end elevational view thereof;

FIG. 4 is a left end elevational view thereof;

FIG. 5 is a side elevational view thereof opposite to that shown in FIG. 2; and

FIG. 6 is a bottom plan view thereof.

FIG. 3
